COKE OVEN WITH GAS RECIRCULATION
MEANS

Cyril William Nash, London, England, assignor to
The Woodall-Duckham Vertical Retort and
Oven Construction Company (1920) Limited,
London, England, a British company

Application February 19, 1949, Serial No. 77,367
In Great Britain February 24, 1948

6 Claims. (Cl. 202—109)

1

This invention concerns improvements in or relating to coke ovens and has particular reference to batteries of coke ovens of the type described in the specification of United States Patent numbered 1,752,363, in which horizontal ovens are arranged side by side with heating flues on either side of each oven, and in which each of these ovens or each of a group of such ovens is connected with common collecting mains for recovering the gas distilled from the coal being carbonized, the said collecting mains being arranged along both sides of the battery (usually at the crown of the latter) and being connected together by an arched offtake main or cross-duct connected—usually centrally—through a T-joint to a suction main through which the generated gases are removed.

The ovens are charged to a predetermined level with coal that is to be carbonized, the coal is levelled, carbonized, and then the coke produced is pushed out of the ovens, all according to a predetermined time cycle or sequence and only at the time that the coke is being pushed out of the ovens are the connections of the oven with the gas mains cut off.

It is very desirable to maintain a substantially uniform temperature throughout the whole depth of the coal bed in each horizontal coke oven in a battery during carbonization of the coal, and various expedients have been tried with little success to achieve this desideratum. As the battery of ovens operates on a time sequence, some ovens will be gassing freely while others in which carbonization is more nearly complete will have more or less stopped gassing. Under the latter condition, there is great danger that the temperature of the oven charge will rise with consequent over-heating of the gas space. Such over-heating causes cracking of the hydrocarbon vapours and ammonia which are formed by the coal carbonization, and thus tends to crack all or part of the by-products and to decrease the value of the by-products obtained. Such a cracking operation also acts to form carbon which builds up on the walls of the oven and which interferes with the heat transference from the heating flues to the oven chamber and the proper carbonization of the coal.

It is proposed in the specification of the co-pending United States patent application No. 627,378 of Koppers Company Inc., now Patent No. 2,541,794, to control the temperature of the gas and vapour in the space at the top of each oven, while permitting the maintenance of the desired temperature in the coke bed, by effecting

5 a positive circulation of cooled gases through the gas space at the top of the oven in alternating directions so as to maintain a substantially uniform temperature in the gas space. The circulated gases are those contained in the gas spaces of the ovens, the collecting mains and the gas off-take mains or arched cross-duct of the battery or group of ovens. As the ovens are usually about 40 feet long it follows that cooled gases 10 passed into one end of an oven gas space from a gas collecting main increase in temperature as they pass through the gas space so that when the gases reach the opposite end of this gas space their temperature is nearly that of the coke bed. 15 It is for this reason that gases in the said circuit comprising the gas collecting mains, gas off-take mains or cross-duct and the gas spaces of the ovens are alternately circulated in opposite directions, this change of direction being effected 20 at frequent intervals so as to bring the cooled gases alternately into the opposite ends of the oven gas spaces in sufficient quantities to maintain a substantially uniform temperature throughout the lengths of these spaces, this temperature being lower than that at which the hydrocarbons and ammonia products will be decomposed.

25 The alternate circulation of the cooled gases in opposite directions is effected, according to the 30 said Koppers patent application No. 627,378, by means of a pair of independent fans arranged one in each vertical part of the arched offtake main or cross-duct and adapted to circulate the gases therein in opposite directions, automatic timing 35 and switch means being provided so as to bring the two fans alternately into operation so that first one fan circulates the gases through the oven gas spaces in one direction and then the other fan circulates these gases in the opposite direction whilst the first fan is at rest, after which the first fan comes into operation again and the second fan rests, and so on throughout the operation of the battery or groups of ovens, it being generally found desirable to effect this 45 reversal of the gas flow direction at about five minute intervals although the duration of these intervals may be varied widely, say between two and sixty minutes, depending for example upon the type of coal being carbonized, the type of coke being made, and the type of gas being produced, it being desirable however to maintain the temperature in the said gas spaces sufficiently low to prevent the decomposition of the by-products being made, as previously explained.

55 An object of this invention is to provide an im-

proved means of effecting an improvement in the said alternate circulation of cooled gases through the gas spaces of the ovens in opposite directions and according to this invention there is provided, in a coke oven battery, a gas duct which is in communication at opposite ends with the gas collecting mains at the opposite sides of the battery, and a rotary fan or impeller (hereinafter referred to as a "fan") which is located in said gas duct for circulating the gases in the gas spaces of the ovens and the said gas collecting mains alternately in opposite directions, such fan being adjustable as to the position of its fan blades in its gas duct so as to be capable itself of causing the said alternating flow of gases by the change in position of the fan blades without change in its own direction of rotation—i. e. without reversing its motor.

The said gas duct containing the said fan may be the arched offtake main or cross-duct of the battery but preferably it is an additional separate gas-duct arranged in parallel with and bridging the said arched offtake main or cross-duct.

According to a further aspect of the invention, there is provided in combination, a battery of horizontal coke ovens arranged side by side, gas collecting mains communicating with the opposite ends of the said ovens at the upper parts thereof, offtake mains extending from each of the said collecting mains to a connecting T, a suction main for leading the gas away from said T, an adjustable rotary fan in a gas duct for drawing gases from one of said collecting mains through said offtake mains and forcing these gases back into the other collecting main and through the gas spaces of the said ovens in one direction and for then drawing gases from the second of the said collecting mains and through the gas spaces of the ovens in the opposite direction to the previous flow, and means for adjusting said rotary fan to alter the position of its blades in its gas duct for causing it alternately to effect the said opposite flow of gases.

According to a further feature of the invention the blades of the said fan are arranged so that their pitches or angles of attack may be adjusted through a range of positive positions, a neutral position and a range of negative positions whereby the fan may be adjusted to give a flow of gases in either direction through the said gas duct or so as to produce a static or "no flow" condition, and whereby the quantitative value of the gas flow in either direction can be regulated.

The fan is preferably driven by a uni-directional continuously operating constant-speed electric motor developing sufficient power for the maximum gas flow required, the actual gas flow being varied as desired by adjustment of the pitch of the blades of the fan and not by adjustment of the running speed of the motor.

Variation of the pitch of the blades of the fan may be provided for by mounting each blade for rotational adjustment about its own axis relatively to the fan shaft.

Thus, according to a further aspect of the invention, there is provided in combination a battery of horizontal coke ovens arranged side by side, gas collecting mains communicating with the opposite ends of the gas spaces of the said ovens at the upper parts thereof, an offtake main leading from each of said collecting mains, a suction main connected to both of said offtake mains at the ends thereof remote from the said collecting mains, a gas duct bridging the said offtake mains, gas circulating means in said brid-

ing gas duct for circulating gases in said collecting mains and offtake mains alternately in opposite directions through the gas spaces of the said ovens, such circulating means comprising a fan in the bridging gas duct having its blades rotatable in its hub to vary and reverse their pitch respectively for effecting a variation in the quantitative flow of said gases thereby, and also to reverse the direction of flow of the gases thereby through the bridging gas duct, means for effecting the variation and reversal of the pitch of said fan blades, and a constant-speed electric motor for driving said fan to run in one direction only.

The rotational adjustment of the blades of the fan may be controlled by any suitable hydraulic, pneumatic, electrical or mechanical means or a combination of such means which itself may be controlled manually or automatically. For example, suitable timing gear may be embodied in the apparatus automatically to control the pitch varying and reversing mechanism of the blades of the fan to effect changes in the quantitative flow of the gas and also the change of direction of the gas flow and, if desired, to provide a variable delay or pause between the change-over from gas flow in one direction to gas flow in the opposite direction. For instance, to effect the said delay or pause the said timing gear may provide for retaining the fan blades, during the reversal of the pitch of the blades, in a neutral position for a predetermined period whilst the fan motor continues to run at its synchronous speed, the fan blades thereafter continuing to move to the position for reversing the gas flow.

In an alternative arrangement, the rotary fan may be of the fixed blade uni-directional type and be mounted in the gas duct for bodily adjustment of the fan blades and their drive shaft through 180° relatively to the duct in order to reverse its direction of thrust, such reversal of the fan as a unitary whole being effected through any suitable hydraulic, pneumatic, electrical or mechanical means (or a combination of such means) which may be remotely controlled or controlled through automatic timing mechanism in a manner similar to that above referred to.

In such an arrangement, means may also be provided for varying the speed of the motor in order quantitatively to control the gas flow through the gas duct.

According to a still further aspect of the invention, there is provided in combination a battery of horizontal coke ovens arranged side by side, gas collecting mains communicating with the opposite ends of the gas spaces of the said ovens at the upper parts thereof, an offtake main leading from each of said collecting mains, a suction main connected to both of said offtake mains at the ends thereof remote from the said collecting mains, a gas duct bridging the said offtake mains, means in said bridging gas duct for circulating gases alternately in opposite directions in said collecting mains and offtake mains and through the gas spaces of the said ovens, said means comprising a rotary fan adjustable as a unitary whole through 180° in said bridging duct to reverse its direction of thrust, means for driving said fan, and means for effecting the adjustment of the said fan as a unitary whole through 180°.

According to a still further feature of the invention, when the fan or fans is or are arranged in a gas duct which is additional to—i. e. which is in parallel with or bridges—the offtake main

or cross-duct, a valve or damper may be provided in the offtake main or cross-duct at the junction of the suction main therewith so as to prevent circulation of the gases in this offtake main or cross-duct, such valve or damper being adapted automatically to reverse its position to place opposite sides of the offtake duct into communication with the suction main each time the said fan in the additional gas duct is operated to reverse the flow of the circulating gases.

It will thus be apparent that this invention provides for the use of a single fan itself adapted to provide alternate flow of the gases in each of the two opposite senses or directions, thus rendering unnecessary a separate fan for driving the gases in each of the said two directions, and eliminating the braking action such fans tend to impose, when idle, on the gas flowing out through the collecting and exhaust mains. However, although only a single fan of the aforementioned character will normally be used for each of said gas ducts it should nevertheless be understood that if desired two or more such fans may be used, these fans being arranged to operate, and be adjusted, in tandem or unison so as to assist one another.

In order that the nature of the invention and the method of carrying the same into effect may be more readily understood two embodiments of the same will now be described by way of example with reference to the accompanying drawings, in which:

Figure 1 is a fragmentary view, partly in elevation and partly in cross-section, showing diagrammatically the upper part of a coke oven battery with its gas collecting mains, offtake mains and the suction main therefor;

Figure 2 is an enlarged diagrammatical vertical part-sectional view of the gas collecting fan shown in Figure 1;

Figure 3 is an enlarged vertical sectional elevation diagrammatically showing the blade controlling mechanism of the fan shown in Figure 2;

Figure 4 shows a modification of Figure 1;

Figure 5 diagrammatically illustrates a modified form of fan unit for use in an arrangement such as is shown in Figure 1; and

Figure 6 is a plan of the unit shown in Figure 5.

In the accompanying drawings, the present invention is shown as applied to a Becker-type coke oven of the kind described in the specification of United States Patent No. 1,752,363.

The coke oven battery is of the horizontal character where therein a series of ovens, such as the oven 1 of which the upper part is shown in Figure 1, are arranged side by side with heating flues (not shown) on opposite sides of each oven. The ovens of such a battery are usually operated as a unit, each of the ovens being connected with gas collecting mains 2 and 3 arranged horizontally one on either side of the battery adjacent the crown 4 thereof and disposed with their lengths perpendicular to the lengths of the ovens 1.

The ovens are provided at the opposite ends respectively with removable sealing doors 5 and 6.

Each oven 1 is charged with coal through charging openings 7 in the crown 4 of the oven after which these openings are sealed. The top of the coal bed 8, in each case, is levelled by a leveller bar which is inserted through an opening 9 in the door 6 of the oven. A space 10 is thus left between the crown 4 of the battery and the top of the coal bed 8 in each oven and this space is herein referred to as "the gas space 10."

The heating flues which are located between the ovens are continuously heated while the battery is in operation and as gases are formed in each oven by the carbonization process these gases rise from the opposite ends of the gas space 10 of the oven and pass upwardly through ascension pipes 11 and 12 arranged one adjacent each end of the battery and respectively connected, by intermediate ductings 13 and 14, to the gas collecting mains 2 and 3.

Preferably arrangements are provided whereby, as the gases pass to the gas collecting mains 2 and 3, they are met by sprays of ammonia liquor introduced through appropriate spray pipes (not shown)—which act to cool the gases to a temperature in the region of 80° C. At this stage the generated gases may also be saturated with water vapour to increase their thermal capacity.

The collecting mains 2 and 3 have the lower ends of vertical portions 15 and 16 of an arched offtake main or cross-duct 21 respectively connected thereto, and these vertical parts of the offtake main continue inwardly respectively in horizontal portions 17 and 18 extending transversely across the top of the battery to a T-joint 19 to which is connected a suction main 20. The arched offtake main 21 is bridged by a gas duct 22 arranged in parallel with the portions 17 and 18 of the offtake main and connected at its opposite ends respectively to the vertical parts 15 and 16 of this offtake main.

The offtake main or cross-duct 21 is conveniently located approximately centrally between the ends of the battery, but it can be arranged in any other suitable position with respect to the battery, for example at one end thereof; moreover, where desired two or more of these offtake mains 21 may be employed at positions spaced along the length of the battery, such offtake mains being connected to separate or to a common suction main.

In order to maintain a more or less uniform temperature in the gas spaces 10 of the ovens whilst retaining the temperature in these spaces below that at which the hydrocarbons and ammonia by-products would be decomposed, cooled gas is circulated through the gas spaces 10 alternately in opposite directions, and to effect this alternating circulation a rotary fan 23 is located within, and preferably centrally between the ends of, the gas duct 22.

The fan 23 has a plurality of blades—e. g. two, three or more—so arranged that their pitches or angles of attack may be adjusted through a range of positive positions, a neutral position and a range of negative positions whereby the fan may be adjusted to give a flow of gases in either direction through the gas duct 22 or to feather and so produce a static or no-flow condition and whereby the quantitative value of the gas flow in either direction can be regulated, this being effected by adjusting the pitches or angles of attack of the blades suitably between the maximum positive or negative positions and their neutral positions.

In the examples shown in the accompanying drawings, which as already stated are of a diagrammatic character, the fan 23 has two diagrammatically opposite similar blades 24 and 25, the roots 26 and 27 of which are rotatably mounted in a cage or hub 28 fixed upon a fan-driving hollow shaft 29. Although the roots 26 and 27 of the blades 24 and 25 are rotatable in the cage 28 they are restrained by any appropriate means 78 against axial movement in this cage.

The shaft 29 is rotatably supported in horizontally spaced bearings 30 and 31 carried by a skeleton supporting structure 32 depending from a housing 34 carried by a vertical trunking 34' built onto the upper side of the cross-duct 22 so that the fan shaft 29 is located coaxially in the gas duct 22.

A constant-speed electric motor 35 is mounted within the housing 34 and drives the fan shaft 29 through pulleys 36 and 37 and a belt 38 which may be a plain belt or of a multiple-section type as desired, suitable means (not shown) being provided for appropriately tensioning the belt or belts.

A fan blade pitch-adjusting or feathering shaft 39 is co-axially mounted in the hollow fan-shaft 29 for axial adjustment on the latter and this feathering shaft projects beyond both ends of the fan shaft. The fan end of the feathering shaft 39 carries a fan-blade feathering head 40 furnished with a pair of racks, 41 and 42 (see Figure 3), arranged opposite each other diametrically of the shaft 29 and parallel to the latter, each of these racks being guided in the cage 28 and meshing with a corresponding toothed wheel fixed coaxially upon the root of the corresponding fan blade 24 or 25, rack 41 meshing with the toothed wheel 43 on the blade 24 being marked in the drawings with a reference 43 and rack 42 meshing with toothed wheel 44 on the blade 25.

The racks 41 and 42 are so arranged with respect to the wheels 43 and 44 that as the feathering shaft 39 is moved axially in one direction in the driving shaft 29, the blades 24 and 25 turn simultaneously and correspondingly in one direction, and as the shaft 39 is moved in opposite directions like rotation of the blades occurs but in a reverse direction so that by appropriately axially adjusting the feathering shaft 39, the blades 24 and 25 can be moved from a maximum positive flow position gradually to a fully feathering or neutral position and then further onwards through gradually increasing negative positions to a maximum flow negative position. Thus, by this means gas can be caused to flow in the gas duct 22 in the direction of the arrows shown in Figure 1 and can subsequently be caused, by reversing the pitches of the blades of the fan, to flow in an exactly opposite direction from that indicated by the arrows. Alternatively the blades can be set in their neutral position so that there is a static or no-flow condition in the duct 22. In addition, by axially adjusting the feathering shaft 39 appropriately, any quantitative value of the gas flow between zero and the maximum capacity of the fan can be achieved in either of the said two directions.

The axial adjustment of the feathering shaft 39 may be effected through a grooved collar 45 fixed on the end of the feathering shaft 39 opposite to that end carrying the fan 23, the axial adjustment of the collar 45 being controlled by a pivoted lever 46. This lever itself is controlled by any suitable means, for example a hydraulically or pneumatically operated piston, an electric motor and screw or by rods and levers, or the lever 46 may be operated through automatic time-controlled mechanism which may include an electric motor (which can be the fan motor 35) furnished with one or more cams for controlling the action of the lever 46.

The arrangement should preferably be such that the duration of the flow of gases in either direction along the gas duct 22 can be varied as

required, and should also provide for the variation in the quantitative flow of gases from the duct in either direction as well as for the variation in the period during which the blades of the fan remain in their no-flow or neutral position, it being desirable, in some cases, to have the blades pause in this position for a period and it is desirable that this period should be variable to suit any particular set of circumstances.

10 The mechanism for actuating the lever 46 for controlling the operation of the pitch of the fan blades is not illustrated in the drawings as it will be clear that a variety of well-known sequence-controlling mechanisms can be adapted for the present purpose.

The fan motor 35 is preferably a constant-speed motor which will run continuously whilst the battery of ovens is operating, variation in the quantity of gas flow along the duct 22 being achieved by modification of the settings of the blades 24 and 25 of the fan 23 rather than by variation in the speed of the motor.

To cool the motor 35 and the fan shaft bearings 30 and 31, the housing 34 is conveniently provided with louvres 47 to admit a certain quantity of air to the housing whilst, if desired, one or more fresh air inlets 48 may be additionally provided to admit outside air (which can be under pressure from a secondary fresh air fan—not shown) into the housing 34 for similar cooling purposes, but this cooling air is not conveyed into the gas duct 22 since the skeleton framework 32, the fan shaft 29 and its bearings 30 and 31, the belt 38 and the mechanism 46 are enclosed by a casing 49. In addition, to the head of the fan 23 is furnished with a spinner 50 and the casing 49 protrudes through a semi-circular flaring 22' which forms a continuation or junction for the gas duct 22 where the casing 49 and the associated parts penetrate into this gas duct.

In the offtake main or cross-duct 21, at the T-joint 19, a valve or damper 51 is provided which is adjustable to segregate either the part 45 18 of the offtake main or the part 17 of the latter from the suction main 20, and this valve 51 is preferably so coupled with the lever 46 or any other suitable part of the fan blade controlling mechanism that the valve 51 reverses its position each time the lever 46 reverses the direction of flow of gases through the duct 22, thereby ensuring that the upper part of the offtake main 21 is excluded from the recirculating system comprising the gas duct 22, the vertical gas offtake 55 main parts 15 and 16, the gas collecting mains 2 and 3, the ascension pipes 11 and 12 and the gas spaces 10 of the ovens.

It will thus be seen that gas is alternately circulated through the gas spaces 10 of the oven from opposite ends, first in one direction and then in the other direction, the rate of change of the direction of circulation and also the quantity of gas circulated being adjusted to provide for the maintenance of the temperature in 65 the gas spaces below that which will be harmful to the by-products which it is desired to produce by the carbonization process.

A modification of the arrangement above described is shown in Figure 4 of the drawings 70 where two of the fan units shown in Figure 1 are used in the gas duct 22, these units being marked respectively 34' and 34'' in Figure 4. Otherwise the arrangement is precisely the same as that described with respect to Figures 1 to 3.

75 Where two or more fans are used in the duct

22 in this way, these fans are arranged to work in tandem or unison so as to operate together and assist one another.

Figures 5 and 6 show a further modification according to this invention wherein, instead of using a variable pitch fan driven by a constant-speed motor, the fan 52 is of the fixed-blade variety but its housing 34a is mounted for rotation by any suitable means, such as meshing bevel gears 53 and 54, through 180° in the duct 22 so that the fan can be arranged to propel gas through the duct 22 in either direction therealong—i. e. reversing the position of the fan blades in the duct 22, without changing the direction of rotation of the fan. In this case, variation in the rate of flow of gas through the duct can be modified to some extent by the rotation of the housing 34 about its vertical axis, but additional variation can be achieved by varying the speed of the motor driving the fan. A substantially no-flow condition would arise when the motor had been turned through 90° from the position shown in Figure 1 but a complete stoppage of flow of the gases through the duct 22 can be achieved by stopping the rotation of the fan altogether.

From the foregoing description, it will be appreciated that apparatus according to this invention enables a proportion of the generated gases (which has not been removed through the suction main but which has been partially cooled by passage through the gas collecting mains) to be recirculated through the gas spaces at the tops of the ovens. When the fan 23 in the gas duct 22 is in the no-flow condition the generated gases do not flow through the gas duct 22; but gas may pass off from both mains 2, 3, in such case, if desired, through the offtake main 21 direct to the suction main 20, the valve 51 being held in a mid-position at this time.

It will be further understood that the apparatus according to this invention comprises a simplification of that described in the said co-pending United States patent application No. 627,378 of Koppers Company Inc. for carrying out the method of recirculation described and claimed in that patent application.

What I claim is:

1. The combination with a battery of horizontal coke ovens arranged side by side, gas collecting mains communicating with the opposite ends of said ovens at their crown spaces in the upper parts thereof, an offtake main leading from each of said collecting mains, and a suction main connected to both of said offtake mains at a position remote from said collecting mains; of a gas duct bridging said offtake mains and by-passing the suction main, means in said bridging gas duct for circulating gases in said collecting mains, through their offtake mains, alternately from one to the other, and thence through the gas crown spaces of said ovens alternately in opposite directions, said circulating means comprising a fan having blades rotatable about their axes to vary and reverse their pitch, respectively, for effecting a variation in the quantitative flow of said gases, and to reverse the direction of flow of the gases, respectively, means for effecting the variation and reversal of the pitch of the blades of said fan, and a constant-speed electric motor for driving said fan.

2. Apparatus as claimed in claim 1, and which includes an adjustable valve controlling the flow of gases alternately from said offtake mains to

said suction main, and means to operate said valve to alternate the connection of said two offtake mains to said suction main in step with the reversal of the pitch of the blades of said fan, for reversal for flow of gases through the said bridging duct.

3. The combination with a battery of horizontal coke ovens arranged side by side, gas collecting mains communicating with the opposite ends of said ovens at their crown spaces in the upper parts thereof, an offtake main leading from each of said collecting mains, and a suction main connected to both of said offtake mains at a position remote from said collecting mains; of a gas duct bridging said offtake mains and bypassing the section main, means in said bridging gas duct for circulating gases in said collecting mains, through their offtake mains, alternately from one to the other, and thence through the gas crown spaces of the said ovens alternately in opposite directions, said means comprising a rotary fan adjustable through 180° in said bridging duct to reverse its direction of thrust, means for driving said fan, and means for effecting the adjustment of the said fan through 180°.

4. The combination with a battery of horizontal coke ovens arranged side by side with heating flues therebetween, gas collecting mains communicating with opposite ends of the gas crown spaces at the upper parts of said ovens, an offtake main leading from each of said collecting mains, and a suction main connected to both of the said offtake mains at a position remote from said collecting mains; of a gas duct bridging the said offtake mains and by-passing the suction main, and fan means in said bridging duct, said fan means comprising an adjustable fan and means to cause said fan to circulate gases cooled in said collecting mains alternately in opposite directions through the bridging duct, from one to the other of the offtake mains, and thence to their collecting mains and through the gas crown spaces of the ovens for reverse flow in alternation therethrough.

5. The combination with a battery of horizontal coke ovens arranged side by side, gas collecting mains communicating with the opposite ends of said ovens at their crown spaces in the upper parts thereof, an offtake main leading from each of said collecting mains, and a suction main connected to both of said offtake mains at a position remote from said collecting mains; of a gas duct bridging the said offtake mains and by-passing the suction main, means in said bridging gas duct for circulating gases in said collecting mains, through their offtake mains, alternately from one to the other, and thence through the gas crown spaces of said ovens alternately in opposite directions, said circulating means comprising a multi-bladed fan having a hub and the roots of the blades rotatably mounted in the hub, a hollow fan shaft on which the hub of the said fan is fixed, an electric motor for driving said fan shaft, a support for suspending the said fan shaft and the fan axially in said bridging gas duct between the ends thereof, gear wheels fixed on the roots of said fan blades, a reciprocable rack for and meshing with each of said gear wheels, a fan blade pitch-adjusting shaft housed in said hollow fan shaft for axial sliding movement relative thereto and having said racks attached thereto at the fan end thereof, and means for axially adjusting said pitch adjusting shaft to vary correspondingly the pitches of all the fan blades simultaneously, for effecting quantitative variation and reversal in

11

direction of gas flow through said bridging duct by said gas circulating means.

6. Apparatus as claimed in claim 5, and in which said fan shaft is located coaxially within said bridging gas duct and said electric motor for driving the fan is disposed outside the outer confines of said duct, all the parts except the fan blades being housed unitarily in a housing let into the upper part of the said gas duct and closed to the interior thereof.
